Patented Jan. 12, 1926.

UNITED STATES PATENT OFFICE.

SAMUEL GOLDBERG, OF NEW YORK, N. Y., ASSIGNOR TO UNIVERSAL FIXTURE CORPORATION, OF NEW YORK, N. Y., A CORPORATION OF NEW YORK.

DISPLAY RACK.

Application filed September 18, 1923. Serial No. 663,405.

To all whom it may concern:

Be it known that I, SAMUEL GOLDBERG, a citizen of the United States, and resident of the borough of Manhattan, in the city, county, and State of New York, have invented certain new and useful Improvements in Display Racks, of which the following is a specification.

This invention relates to improvements in display racks, and has for its objects to provide a strong and durable rack of simple and inexpensive construction adapted to removably support a maximum number of rolls of fabric for convenient inspection while in the rack and for convenient removal from the rack when desired; to provide a storage and display rack for rolled fabrics of large capacity but occupying a minimum of floor space; to provide a knock-down display rack for rolled fabrics; and to provide a rack having independently adjustable supporting means for a plurality of rolls of fabric.

In the accompanying drawings, Figure 1 is an end elevation of the rack; Fig. 2 a front elevation; Fig. 3 a plan view; Fig. 4 a section on the line 4—4 of Fig. 1; and Fig. 5 a fragmentary perspective view of the lower portion of the rack.

The rack is of skeleton steel construction and comprises two storage sections A and B spaced apart longitudinally of the rack and connected with each other only at the top of the rack so that persons may enter freely to passageway C between the two sections for convenient access to rolls of fabric stored at the inner sides of the two sections of the rack. Each of the sections A and B is preferably of oblong shape in plan view, as shown, and the sections are arranged with the longer sides thereof extending transversely of the rack.

Each rack section comprises four vertical corner posts 10 formed of steel angle bars each having one web extending longitudinally of the rack and its other web extending transversely of the rack. The two front corner posts are connected together at the top and bottom of the section by two pairs of crossed flat steel brace bars, and the two rear corner posts are also connected together at the top and bottom of the section by two pairs of crossed flat steel brace bars, said four pairs of brace bars being designated 11

in the drawings and being detachably secured at their ends to the longitudinally extending webs of the corner posts. The two outer corner posts of each section are connected together at their upper and lower 60 ends by crossed metal tension rods 12 each formed in two sections connected together by a turnbuckle 13. Braces 11 are detachably held to the corner posts by nut-and-bolt fastenings 14.

The four posts 10 at each longitudinal side of the rack are connected by a pair of steel brace bars 15 of angle form, which extend longitudinally of the rack, with one web depending at the outer faces of the webs of the corner posts which extend longitudinally of the rack and are detachably held thereto by bolt-and-nut fastenings 16, and the other web thereof disposed horizontally and seated on the upper ends of the corner posts. Three of the nut-and-bolt fastenings 14 for each pair of brace bars 11 at the bottom of the rack are ordinary screw-headed bolts and nuts, while the fourth one of said fastenings comprises the threaded lower end 80 of the adjacent tension rod 12 which passes through one corner post and one brace and has a nut threaded on its outer end. The two intermediate fastenings 16 for each brace bar 15 are ordinary screw-headed bolts 85 and nuts, while the two end fastenings for each bar comprise the threaded upper ends of the adjacent tension rods 12 which pass through the corner posts at the ends of the rack and through the depending web of the 90 brace and have nuts threaded on their outer ends.

A pair of longitudinally extending steel brace bars 17 of angle form are secured at their ends by bolt-and-nut fastenings 18 to the inner corner posts of the rack sections, said bars 17 extending across passage C at the front and rear of the rack and being located slightly below bars 15 at a level substantially higher than the height of the 100 average person, and being bolted against the outer faces of the corner posts. The two outer corner posts and the two inner corner posts of each rack section are detachably connected at their lower ends by nut-and-bolt fastenings 19 to the vertical webs of a pair of transverse steel brace bars 20, the horizontal webs of said angle bars 20 being flush with the lower ends of the corner posts 105 of the rack and adapted to rest upon a floor. 110

The corner posts of the rack sections are connected at their upper ends by bolt-and-nut fastenings 21 to the ends of the vertical webs of transverse steel brace bars 22 of angle form overlying bars 20, said bars 22 having the ends of their horizontal webs abutting against the under faces of the horizontal webs of bars 15 and detachably held thereto by nut-and-bolt fastenings 23. A pair of crossed steel tension rods 24 are connected at their ends with brace bars 15 near the ends of said bars, the ends of said rods being threaded and passed down through the horizontal webs of the bars and having nuts 25 screwed on their lower ends. Each rod 24 is divided into two sections connected by a turnbuckle 26.

The parts above described constitute a rigid skeleton rack frame made up of simple and light steel units detachably connected together in such manner that said frame may be readily assembled and readily knocked down when desired. The various structural members are straight rods, flat bars, or straight angle bars adapted to be packed in compact form when knocked down. The vertical webs of the corner posts 10 which extend longitudinally of the rack are each provided with a vertical series of bolt holes 27 whereby a plurality of superposed steel saddle bars 28 may be detachably secured in various vertically adjusted positions by bolt-and-nut fastenings 29 to the outer faces of said webs at both ends of each section A and B of the skeleton main frame of the rack. The saddle bars 28 of each storage section A and B extend longitudinally of the main frame and project slightly beyond the adjacent outer ends of the main frame at their outer ends and slightly across passage C at their inner ends. The vertical webs of the projecting end portions of saddle bars 28 are notched at their upper edges to provide a concave rod saddle or seat 30 in each of said projecting ends of the bars, and are also notched midway their ends to provide a third concave rod saddle or seat 30 in each bar midway between the corner posts of the frame section to which the bars are bolted. Three vertical rows of steel supporting rods 31 for rolls of fabric are removably held in each frame section of the rack, said rods extending transversely of the rack between saddle bars 28 and being seated near their ends in the saddles or notches 30 in said bars. As the rack is substantially higher than the average person, it is necessary for a person in placing a roll D of fabric wound upon one of the rods 31 in place upon the two uppermost pairs of saddle bars of each

rack section to reach upwardly. In order to facilitate seating of the rods in notches 30 in the ends of these higher saddle bars, said bars are provided near each end with two vertical extensions 28^a of the vertical webs thereof, the outer edges of which extensions incline upward and inward from the inner edges of the end notches 30 to the upper ends of said extensions at points flush with the adjacent edges of the corner posts 10. The rods 31 may thus be thrust up against extensions 28^a and will then automatically slide down into the adjacent seats in the saddle bars. Rods to be seated in the central saddles may be passed up between the saddle bars and rolled along the top edges of the bars until they drop into the saddles.

The fixture is adapted to support a large number of rolls of fabric of various diameters without any roll having to sustain the weight of another roll. It has a large capacity, but occupies relatively little floor space. It will also be noted that the several rolls may be readily inspected while in the rack, and may be readily removed and replaced when desired.

What I claim is:

A rack for fabrics in the roll, comprising two spaced upright frame sections each section being rectangular in horizontal section and formed of four vertically arranged corner angle-irons each of said angle-irons being formed with a vertical series of bolt apertures in its vertical end members, transverse rods rigidly and detachably connecting together the vertical angle bars of each frame section at the upper and lower ends thereof, detachable truss means connecting the top and bottom of each section, means detachably connecting together the upper ends of the two frame sections to stabilize them and hold them rigidly spaced apart to form an arched passageway therebetween, and a series of saddle-bars adjustably and detachably bolted through said bolt apertures to each adjacent pair of corner-irons of each frame section, these saddle bars lying in planes at right angles to the passageway between the frames and each having its ends projecting beyond the frame section and provided with bearings for the fabric roll shafts at said projecting ends and midway the ends, whereby the fabric rolls may be displayed at the center of each section and upon the inner and outer sides thereof and will project between the aforesaid corner-irons.

In testimony whereof I hereunto affix my signature.

SAMUEL GOLDBERG.
